(57) **CLAIM**

The ornamental design for a portable car seat cooling device, as shown and described.

DESCRIPTION

FIG. 1 is a perspective front view of a portable car seat cooling device;

FIG. 2 is a front elevation view of the portable car seat cooling device;

FIG. 3 is a rear elevation view of the portable car seat cooling device;

FIG. 4 is a left side elevation view of the portable car seat cooling device;

FIG. 5 is a right side elevation view of the portable car seat cooling device;

FIG. 6 is a top plan view of the portable car seat cooling device;

FIG. 7 is a bottom plan view of the portable car seat cooling device; and,

FIG. 8 is a perspective front view showing the invention in an in-use orientation with cooling packs partially inserted.
